CLAIM

The ornamental design for an escutcheon, as shown and described.

DESCRIPTION

FIG. 1 is a front perspective view of an escutcheon showing my new design.

FIG. 2 is a rear perspective view thereof.

FIG. 3 is a front elevational view thereof.

FIG. 4 is a rear elevational view thereof; and,

FIG. 5 is a side elevational view thereof.

The broken lines are for illustrative purposes only and form no part of the claimed design.
